(57) **CLAIM**

The ornamental design for a medical coagulation and ablation blade, as shown and described.

DESCRIPTION

FIG. 1 is a right perspective view of a medical coagulation and ablation blade

FIG. 2 is a front view thereof;

FIG. 3 is a rear view thereof;

FIG. 4 is a right side view, the left side being a mirror image thereof;

FIG. 5 is a bottom left perspective view thereof;

FIG. 6 is a top view thereof;

FIG. 7 is a bottom view thereof; and,

FIG. 8 is an exploded view thereof.

The broken lines shown in FIGS. 1-8 illustrate portions of the medical coagulation and ablation blade that form no part of the claimed design. The additional broken lines shown in FIG. 8 illustrate environment and form no part of the claimed design.
